US00D920247S

(12) **United States Design Patent** (10) Patent No.: **US D920,247 S**
(45) Date of Patent: **** May 25, 2021**

(54) **CURRENT TRANSDUCER**

(71) Applicant: **LEM Intellectual Property SA**,
Fribourg (CH)

(72) Inventor: **Xuyang Liu**, Beijing (CN)

(**) Term: **15 Years**

(21) Appl. No.: **35/508,918**

(22) Filed: **Sep. 24, 2019**

(80) **Hague Agreement Data**

Int. Filing Date: **Sep. 24, 2019**

Int. Reg. No.: **DM/204500**

Int. Reg. Date: **Sep. 24, 2019**

Int. Reg. Pub. Date: **Mar. 27, 2020**

(51) LOC (13) Cl. **13-02**

(52) U.S. Cl.

USPC **D13/110**

(58) **Field of Classification Search**

USPC D13/110, 101, 117, 123; D10/79

CPC .. G01R 19/0092; G01R 15/202; H02J 7/0045

(57) **CLAIM**

The ornamental design for a current transducer, as shown and described.

DESCRIPTION

1. Current transducer
- 1.1 : Perspective
- 1.2 : Perspective
- 1.3 : Front
- 1.4 : Back
- 1.5 : Top
- 1.6 : Bottom
- 1.7 : Left
- 1.8 : Right
